CLAIM

The ornamental design for mini-fluorescent light, as shown and described.

DESCRIPTION

FIG. 1 is a perspective view showing the mini-fluorescent light design;

FIG. 2 is a bottom plan view;

FIG. 3 is a rear elevation view;

FIG. 4 is a front elevation view;

FIG. 5 is a top plan view;

FIG. 6 is a side elevation view of the first side;

FIG. 7 is an elevation view of the side opposite from the first side;

FIG. 8 is a bottom side perspective view of an alternate embodiment;

FIG. 9 is a top side perspective view of the alternate embodiment of FIG. 8;

FIG. 10 is a side elevation view of one side of the alternate embodiment, the other side being a mirror image thereof; and,

FIG. 11 is a rear elevation view of the alternate embodiment of FIG. 8.
